Primary Examiner — Leanne Was-Englehart(74) *Attorney, Agent, or Firm* — Sheridan Ross P.C.(57) **CLAIM**

The ornamental design for a bucket grating section, as shown and described.

DESCRIPTION

FIG. 1 is a perspective view of a bucket grating section showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines show portions of the bucket grating section which form no part of the claimed design.
